UNITED STATES PATENT OFFICE.

WILLIAM HEIB, OF AKRON, OHIO.

DESIGN FOR AN EAVES-TROUGH HANGER.

SPECIFICATION forming part of Design No. 30,108, dated January 31, 1899.

Application filed August 19, 1898. Serial No. 689,019. Term of patent 7 years.

To all whom it may concern:

Be it known that I, WILLIAM HEIB, a citizen of the United States, residing at Akron, in the county of Summit and State of Ohio, have invented and produced a certain new and original Design for an Eaves-Trough Hanger, of which the following is a specification.

As shown in the drawings, in which Figure 1 is a side elevation and Fig. 2 a front elevation, my design presents the appearance of three wires 1, 7, and 10, peculiarly bent and retained by a fastening-pin. The peculiar appearance of bending of the several wires 15 presents the wire 1 as bent at the center in a loop 2 and then alternately inward and outward, touching and forming loops 3 4 5, and a further loop 6 at a right angle with the former loops, and above this last loop it appears twisted for a considerable length, and 20 the ends bent downward parallel with each other and the apparently twisted portion, and bent and fastened in the loop 6. This upper portion is bent outward at an angle of about 25 sixty degrees, and the portion representing the second wire 7 appears bent at its center, so that the two halves lie parallel, curved to

inclose the roll of the trough at the point 8, and thence curved to conform to the trough and bent alternately inward and outward, 30 forming loops 3 4 of the other portion, and with its free ends twisted together and bent forward and downward to form a hook 9, adapted to engage and hold the back of the trough. The wires 1 and 7 are apparently 35 united by a third wire 10, bent at its center to form a loop 11, small enough to enter the loops 3 4, and thence bent at a right angle and again upward at the point 12 and its ends bent upward at 13. These bent ends appear 40 passed through the loop 4 of the wire 1 and 7 and rocked down, with its looped end passed through the loop 3 and retained by a nail 14, passed through the loop 11.

I claim as my invention—

The design for an eaves-trough hanger as herein shown and described.

In testimony that I claim the above I hereunto set my hand.

WILLIAM HEIB.

In presence of—

C. E. HUMPHREY,
C. P. HUMPHREY.
